UNITED STATES PATENT OFFICE.

DANIEL M. HARRIS, OF JOHNSTOWN, AND JESSE W. BAIR, OF FERNDALE BOROUGH, PENNSYLVANIA.

CAR DUMPER.

Application filed April 15, 1920. Serial No. 374,144.

To all whom it may concern:

Be it known that we, DANIEL M. HARRIS and JESSE W. BAIR, both citizens of the United States, the former residing in the city of Johnstown, county of Cambria, and State of Pennsylvania, and the latter residing in the borough of Ferndale, county of Cambria, and State of Pennsylvania, have invented certain new and useful Improvements in Car Dumpers; and we do hereby declare the following to be a full, clear, and exact description of the invention, such as will enable others skilled in the art to which it appertains to make and use the same.

Our invention relates to car dumpers in which gravity causes the cars to follow a path of such outline that the cars in their passage through the dumper are automatically inverted, emptied and righted, and it also relates to means adapted to control the speed and movement of the cars in their passage through the dumper.

Our invention is shown and described in connection with mining operations and is for the purpose of emptying cars containing ore, coal, stone or other materials and depositing the same in a convenient place for further handling, and although, it is particularly adapted to the above uses, we wish it understood that our invention is not limited to or defined by the particular applications mentioned as it may be used in other connections and arts by those skilled therein without deviating from the intent or purpose of this specification.

One of the objects of our invention is to provide an automatic car dumper in which the cars are actuated by gravity, thereby eliminating power requirements and effecting a considerable saving in labor as compared with the present types of mechanical power dumpers.

Still another object of our invention is to provide a car dumper with suitable retarding devices adapted to control the speed and movement of the cars in their passage through the dumper.

A further object of our invention is to provide a car dumper of simple design and construction which has no moving parts except those included in the retarding devices and will therefore assure a great saving in wear, repairs, renewals and maintenance,

and at the same time provide constant service.

A still further object of our invention is to provide a car dumper that will permit the use of different types of cars and especially solid end cars, although cars with swinging end gates may be used if desired. The solid end car is preferable to the swinging end gate car because of its tight, rigid and stable construction. The solid end car therefore eliminates the damages and loss from dust, loss of material and the consequent collection of same along the haulage roads and eliminates maintenance charges, that arise from the unstable construction of other types of cars.

Other objects of our invention are to provide a car dumper that can be used with different kinds of mine openings, such as slopes, shafts or drifts and will also allow sufficient head room for screens, picking tables, etc., or for trucks, cars, or other devices. Furthermore, our car dumper is arranged to reduce breakage of the material handled to a minimum.

Our invention comprises a framework, on which is mounted a trackway that is provided with retarding or braking devices adapted to control the speed of the cars in their passage through the dumper. The trackway comprises an entrance track, a pair of opposed curvilinear tracks spaced apart and adapted to engage the car wheels on opposite sides of the centers thereof, and a delivery track. The shape of the trackway is such that gravity actuates the cars throughout their passage in the dumper and a loaded car entering the trackway in the normal or upright position, is inverted, emptied and righted, whereupon it leaves the dumper on the delivery track, which may be connected with a kick-back or other well known means adapted to dispose of the empty cars. The material dumped out of the cars falls into a hopper and chute or discharging device mounted on the framework, where it is available for distribution to screens, picking-tables, etc., or to trucks, cars or other devices.

Having thus given a general description of our invention, we will now, in order to make the matter more clear, refer to the two accompanying sheets of drawings, which forms part of this specification and

on which like characters of reference refer to like parts.

Figure 1 is a vertical longitudinal sectional elevation of our improved car dumping apparatus taken on the line I—I of Figure 2, showing a mine car beginning its dumping movement;

Figure 2 is a vertical transverse sectional elevation taken on the line II—II of Figure 1;

Figure 3 is a partial horizontal sectional view taken on the line III—III of Figure 1; and

Figure 4 is a detail sectional view of a cushion provided for the upper movable track section.

Referring now to the characters of reference on the drawings:—1 indicates the framework in general of the car dumper which is preferably constructed from structural steel shapes designed so as to produce a strong and rigid structure. Rails 2 and 3 attached to brackets 4 mounted on the framework 1 form opposed curvilinear tracks adapted to guide the car 42 in its passage through the dumper. In order that the speed of the cars in their passage through the dumper may be properly controlled, suitable retarding devices are provided.

30 The retarding devices comprise movable track sections adapted to decrease the distance between the tracks 2 and 3 and thus to bear against the car wheel treads, thereby slowing up the car at the will of the operator.

35 The movable track sections consist of movable rails 5 and 6 suspended from the structural members 9 and 10 respectively at the points 7 and 8 respectively. The brackets 4 which support the movable rails 5 and 6 have the end 45 of one arm bearing against 40 filler plates 44 which are secured to the movable rails 5 and 6.

The movable rails 6 are provided with cushions shown in detail in Figure 4. Each 45 of these cushions has a spring 12 adapted to press against the buffer blocks 11 which are secured to the movable rails 6. The casting 14 houses the spring 12 and the disk 13 and is secured to the structural member 18, 50 together with the flanged boss 16 by the bolts 17. The adjusting screw 15 engages the flanged boss 16 and bears against the disk 13 and is therefore adapted to vary the compression in the spring 12.

55 The upper pair of buffer blocks 11 have journaled therein the shaft 19 which passes through one end of the eccentric rods 20. The eccentric rods 20 engage the eccentrics 21 mounted on the eccentric shaft 22, which 60 has secured thereto the crank 23. The crank 23 is connected with the crank 25 on the operating shaft 26 by the link 24. The operating shaft 26 is mounted in bearings secured to the structural member 27. Secured to the 65 operating shaft 26 is a manually controlled

lever 29 which is adapted to engage the toothed sector 28 mounted on the controlling stand. The operating shaft 26 also has secured thereto the crank 30 which is connected with the crank 32 on the shaft 33 by the link 31. The shaft 33 is mounted in bearings secured to the structural member 34 and has secured thereto the crank 35. The links 36 connect the cranks 35 to the shaft 37, which is mounted in bearings 38 secured to the movable rails 5.

It is therefore evident that, by moving the controlling lever 29 in the desired direction, the operator can shift the movable track sections and thus decrease or increase the distance between the tracks, thereby producing any desired braking or decelerating of the car wheels 43, the amount of which can be so graduated as to permit passage of cars through the dumper at speeds consistent with safety. It is also evident that the speed of the car can be controlled on two independent track sections, i. e. the one formed by the movable rails 6 and the other by the movable rails 5, or when the car wheels engage both movable track sections, each can be operated to exert a resistance adapted to decrease the speed of the car. Furthermore the movable track sections can be arranged to operate individually or collectively.

In the operation of our car dumper, a car comes in from the haulage-way or mine opening on to the inclined entrance track 46 at the top of the dumper, whence the car 42 actuated by gravity passes along the opposed curvilinear tracks to the position shown by the full lines in Figure 1. At this point the car 42 is beginning to tilt and discharge its load which has but a short distance to fall on to the inclined surface of the top portion 39 of the hopper 40, whence it slides into the hopper 40. As the car 42 passes on between the upper portions of opposed curvilinear tracks its speed is controlled by the operator who moves the controlling lever 29, thus actuating the retarding device as heretofore described. Finally the car 42 reaches the inverted position shown by the dotted lines in Figure 1 and has then emptied its entire load into the hopper 40 from which the material is available for distribution through the chute 41 to screens, picking tables, etc. or to trucks, cars or other devices. If the delivery track 47 is not clear, the car 42 can be held in the inverted position shown in dotted lines in Figure 1 by the retarding device actuating the movable rails 5. If clear, however, the car passes on around the lower portion of opposed curvilinear tracks and is thereby righted, whence it leaves the dumper on the delivery track 48, shown in dotted lines on Figure 1, to a kick-back or on the delivery track 47, shown in full lines on Figure 1, to

any well known means adapted to dispose of the empty cars.

The essential portion of the apparatus comprising our car dumper is a track arranged in the form of an upright reverse curve with an entrance track, preferably inclining downwardly toward the first portion of the curve and with a delivery track which either may be inclined downwardly, level or inclining upwardly from the delivery end of the lower curved track, the delivery track being so arranged as to slightly retard the motion of the car preparatory to delivering it to a switchback or to another track for further use. In other words, our trackway may be generally arranged in the form of an upright S-curve in a sinuous manner in upright direction. We prefer, of course, to arrange the curves substantially vertical, but they need not be exactly vertical, although they are upright.

The advantages of our invention are readily apparent, for it provides a car dumper that insures economy and efficiency in operation, since it requires no power and needs but one man to operate it. Furthermore, it is adapted to handle different types of cars and particularly the solid end car, which has so many advantages over other types of cars, and yet is not available for use in many of the present car dumper. Our car dumper also handles materials with the breakage thereof reduced to a minimum and yet deposits the material in a convenient place for further distribution. The different kinds of mine openings to which our car dumper is adapted and the convenient head room which it assures also add to its advantages. The absence of movable parts except those included in the retarding devices assures low maintenance charges on our car dumper and the retarding devices which are relatively simple and yet efficient have but few parts that are subject to wear.

Although we have shown and described our improvements in considerable detail, we do not wish to be limited to the exact and specific details shown and described, but may use such substitutions, modifications or equivalents thereof, as are embraced within the scope of our invention, or as pointed out in the claims.

Having thus described our invention, what we claim and desire to secure by Letters Patent is:—

1. A car dumper comprising a continuous track with inclined and vertically curved

portions, and friction means for retarding the movement of a car thereon.

2. A car dumper arranged in an upright 60 sinuous manner and provided with friction means for retarding the movement of a car thereon.

3. A car dumper comprising a track having the general form of an upright S-curve, 65 another track portion substantially parallel to and opposite a portion thereof, and means for moving said latter track to or from the track aforesaid, thereby retarding the movement of a car thereon.

4. A car dumper comprising a trackway provided with two opposed tracks spaced apart and having the general form of an upright reverse curve, entrance and delivery tracks connected with the upper and 75 lower ends respectively of one of said opposed tracks, a movable track portion in one of said opposed tracks and means for actuating said movable track portion to or from the other track.

5. A car dumper comprising a trackway having two substantially parallel tracks in the general form of a vertical reverse curve, entrance and delivery tracks connected with one of said parallel tracks, movable portions in one of said tracks, and means for actuating said movable portions to or from the other track.

6. A car dumper, including a continuous trackway comprising entrance and delivery 90 tracks and intermediate therebetween two opposed tracks arranged substantially parallel and having the general form of an upright reverse curve, friction means adapted to control the movement of a car on said trackway, and a material receiving means mounted below the upper portion of the curve.

7. A car dumper comprising a track provided with inclined entrance and delivery 100 tracks and an intermediate portion in the general form of a vertical reverse curve, a second track opposite and substantially parallel to the intermediate portion of the first track, movable track portions in the first 105 track, means adapted to actuate said movable track portions, and a material receiving dumper, a hopper adapted to receive the material dumped from the car, and a chute leading from said hopper.

In witness whereof we hereunto affix our signatures.

DANIEL M. HARRIS.
JESSE W. BAIR.
